UNITED STATES PATENT OFFICE.

ALBERT J. MATTER, OF CHICAGO, ILLINOIS.

DESIGN FOR AN AUTOMOBILE DIRECTION-INDICATING LENS.

Application filed August 3, 1925. Serial No. 14,311. Term of patent 14 years.

To all whom it may concern:

Be it known that I, ALBERT J. MATTER, a citizen of the United States, residing at Chicago, in the county of Cook and State of Illinois, have invented a new, original, and ornamental Design for Automobile Direction-Indicating Lens, of which the following is a specification, reference being had to the accompanying drawing, forming part thereof.

In the drawing:

Fig. 1 is a side elevational view of a lens embodying my invention and Fig. 2 is an end view of the same.

I claim:

The ornamental design for an automobile direction indicating lens, as shown.

ALBERT J. MATTER.
